PIPE AND FITTING GAUGE

Michael G. Zahariades, West Haven, Conn.

Application September 25, 1958, Serial No. 52,764

Term of patent 14 years

(Cl. D52—1)

Fig. 1 is a top plan view of a pipe and fitting gauge embodying my new design; and

Fig. 2 is a sectional view thereof taken on line 2—2 of Fig. 1.

I claim:

The ornamental design for a pipe and fitting gauge, substantially as shown.
